UNITED STATES PATENT OFFICE.

EDWARD M. SEARS, OF AKRON, OHIO, ASSIGNOR TO THE B. F. GOODRICH COMPANY, OF NEW YORK, N. Y., A CORPORATION OF NEW YORK.

DESIGN FOR A TIRE.

Application filed July 18, 1926. Serial No. 18,347. Term of patent 14 years.

To all whom it may concern:

Be it known that I, EDWARD M. SEARS, a citizen of the United States, residing at Akron, in the county of Summit and State of Ohio, have invented a new, original, and ornamental Design for a Tire, of which the following is a specification, reference being had to the accompanying drawing, forming a part thereof.

Fig. 1 is a plan view of a pneumatic tire casing showing my design.

Fig. 2 is a cross-section on the line 2—2 of Fig. 1.

I claim:

The ornamental design for a tire as shown.

EDWARD M. SEARS.
